UNITED STATES PATENT OFFICE.

SAMUEL LLOYD BOULDIN, OF OSWEGO, KANSAS.

TRAIN-COALER.

1,398,833.

Specification of Letters Patent. Patented Nov. 29, 1921.

Application filed October 16, 1920. Serial No. 417,354.

To all whom it may concern:

Be it known that I, SAMUEL LLOYD BOULDIN, a citizen of the United States, residing at Oswego, in the county of Labette and State of Kansas, have invented new and useful Improvements in Train-Coalers, of which the following is a specification.

This invention relates to improvements in apparatus designed particularly for use in 10 coaling trains, while in motion, such means providing for the control by the approaching train of the discharge from the coal hopper, so that the coal will be delivered to the tender without the necessity of stopping the train.

The invention contemplates the use of a coal hopper into which the coal may be dumped from any suitable carrier, the hopper having a hinged bottom controlled by a 20 latch, there being means arranged along the sides of the railway track for tripping the latch to release the bottom and permit the discharge of coal. A co-operating means is arranged in the engine and the latter is adjusted by the engineer in accordance with the speed of travel of the train, so that a 25 particular portion of the track carried tripping means will be operated in order that the discharge of coal may be had when the tender is beneath the hopper.

The nature and advantages of the invention will be better understood when the following detail description is read in connection with the accompanying drawings, the 35 invention residing in the construction, combination and arrangement of parts as claimed.

In the drawings forming a part of this application like numerals of reference indicate similar parts in the several views and wherein:

Figure 1 is a view in elevation showing the track, the coal hopper arranged above the same and a trip mechanism arranged on 45 the track.

Fig. 2 is a plan illustrating the track carried trip mechanism.

Fig. 3 is an enlarged bottom plan of the coal hopper showing particularly the latch 50 mechanism.

Fig. 4 is a side elevation of the coal hopper showing the means for returning the hinged bottom to closed position following the discharge of the coal.

Fig. 5 is a detail view of the trip mechanism arranged on the track.

Fig. 6 is a view in elevation showing the engine carried means whereby the trip mechanism or the particular portion thereof is operated by the engineer.

Fig. 7 is a side elevation of the engine carried means.

The coaling apparatus includes a hopper 1 of appropriate size supported above the track 2 and preferably provided with tracks 65 3 leading from the usual support and arranged adjacent the upper end of the hopper so that the coal cars of convenient type may be run on said track 3 and discharged into the hopper to fill the latter. The hopper is provided with a bottom closure 4 hinged at 5 to one side wall of the hopper and provided with extended arms 6 having terminal weights 7, the weights being of a capacity to close the bottom 4 when the 75 contents of the hopper have been discharged.

Secured on the bottom of the hopper is a latch mechanism including a latch bar 8 slidably mounted at 9 and operated in the latching direction by a spring 10. The bottom 4 of the hopper is provided with a keeper 11 with which the nose end of the latch bar 8 is adapted to engage to hold the bottom in closed position and support the load of coal within the hopper. An arm 12 85 is secured to the latch bar 8 and projects laterally thereon in order to provide the desired leverage for the convenient operation of such latch bar against the weight of the load of coal. A cable 13 is connected to one end of the arm 12 and is in turn connected to oppositely disposed cables 14 and 15, the latter passing over fixed pulleys 16 arranged upon any convenient support. The cables 14 and 15 extend in opposite directions lengthwise of the track 2 and pass over suitable guides and the sustaining pulleys 17, the free end of the respective cables being connected to a plurality of depending arms herein shown at 21, 22 and 23. The 95 arms just mentioned are pivoted at their upper ends as at 24 and connected with the cables as at 25. As illustrated the arms 21, 22 and 23 are of successive increased length for a purpose to be presently described.

Carried by the engine is an inverted substantially U-shaped trip element 26, the parallel limbs 27 of which are connected at

a point in their length by a cross piece 28. The limbs 27 of this trip element are slidable through guides 29 carried by the engine, the limbs 27 being carried at the opposite sides 5 of a slot 30 provided in the engine. An operating lever 31 is pivoted at a point between its ends as at 32 upon a bracket 33 which bracket is formed with a toothed segment 34. The lever 31 has a slotted portion 35 which projects through the slot 30 of the engine, the cross piece 28 of the trip element 26 passing through the slot 35 of the lever. Manifestly the trip element 26 is operable at the will of the engineer and so 10 arranged that when projected a certain distance above the engine, said element will engage the final and longest arm 23, the trip element 26 being maintained in the positions just mentioned by means of a dog 15 36 engaging one tooth of the segment 34. The element 26 may be adjusted to the proper distance above the engine to engage any one of the three arms indicated at 21, 22 and 23. With the hopper 1 loaded with 20 coal, the engineer will set the trip arm in accordance with the speed of the train at the time a load is being dumped. If traveling at a certain speed, for example ten miles an hour, he will set the element 26 to engage 25 the first and shortest arm 21 of the trip mechanism. The relative arrangement of the parts just described is such that under the conditions the latch bar 8 will be operated and the bottom released so that the 30 tender will reach a position below the hopper as such bottom is released and the load from the hopper discharged. For faster speed, the other arms 22 and 23 are tripped as desired, discharging the coal at the proper 35 interval, in accordance with the speed of travel of the train.

While it is believed that from the foregoing description the nature and advantages of the invention will be apparent, I desire 40 to have it understood that I do not limit myself to what is herein shown and de-

scribed and that such changes may be resorted to when desired as fall within the scope of what is claimed.

What I claim is:—

1. A coal loading device comprising a hopper arranged above the track, a bottom hinged to the hopper, means for holding the bottom in closed position, arms of different lengths pivoted above the track, a cable for tripping said means, said cable being connected with said arms, and a trip bar carried in the locomotive and adapted to be set to engage the desired arm in accordance with the travel of the train. 50

2. A coal loading device comprising a hopper arranged above the track, a bottom hinged thereon, means carried by the bottom for automatically closing the same when the load has been discharged, a latch bar 65 for latching the bottom in closed position, cables connected to said latch bar for operating the same, a plurality of arms pivoted above the track and connected to said cables, said arms being of different lengths with the 70 arm of greatest length nearest the hopper, and means carried by the engine to selectively operate either of said arms.

3. A coal loading device comprising a hopper, arranged above the track, a hinged bottom therefor, means for holding the bottom in closed position, a cable for tripping said means, a plurality of arms pivoted above the track and connected with said cable and said arms being of different lengths with the 75 arm of greatest length arranged nearest the hopper, means carried by the engine to selectively operate either of said arms in accordance with the travel of the train, and said means comprising a trip element carried by the locomotive for vertical adjustment at the will of the engineer, and means for holding the element at the desired degree of elevation for the purpose specified. 80

In testimony whereof I affix my signature. 85

S. LLOYD BOULDIN.
